UNITED STATES PATENT OFFICE.

EDMUND C. HEYN, OF CATONSVILLE, MARYLAND, ASSIGNOR TO THE B. V. D. COMPANY, OF NEW YORK, N. Y., A CORPORATION OF DELAWARE.

UNDERGARMENT.

1,280,027.

Specification of Letters Patent. Patented Sept. 24, 1918.

Application filed September 5, 1913. Serial No. 788,228.

To all whom it may concern:

Be it known that I, EDMUND C. HEYN, a citizen of the United States, and a resident of Catonsville, Maryland, have invented certain new and useful Improvements in Undergarments, of which the following is a specification.

The invention relates more particularly to a garment popularly known as a union suit and has for its object the provision of a proper crotch construction.

Generally speaking the garment to which particular reference will be made in this specification is the widely known B. V. D. union suit made in accordance with the disclosure of the Walker Patent No. 852,306 of April 30, 1907. In union suits of that kind both the right and the left legs have always been made on identically the same patterns with the result that in the various movements of the human body the two halves of the garment acted in an exactly similar manner. The garment constructed according to those principles does not conform to the requirements with respect to the crotch construction. In other garments many attempts have been made to improve the crotch construction and in almost every case this has resulted in a device wherein the garment is closed in the crotch. I have found, however, that very improved results will follow if the garment is not closed at the crotch but if the garment is so constructed that while permitting ample lateral freedom of motion with respect to the fabric situated in the crotch there shall be at all times a portion of the fabric composing the under-garment interposed in the crotch between the person of the wearer and his outer garments.

In carrying out this idea I have discovered that a proper construction based upon these principles is such a one in which it is apparently the outer layer of the under-garment and not the under-layer in the crotch region, which should be the prominent crotch over-lapping part. In order to carry out this idea I have found it expedient that the part which apparently is the under-lapping part in the crotch region should be reduced in the lateral direction so as to be as far removed as possible from the crotch itself without interfering with the natural requirements of a union suit.

55 The invention is illustrated in the accom-

panying drawings in which Figure 1 illustrates a front view of the garment; Fig. 2 a rear view thereof below the waist line; Figs. 3, 4 and 5 illustrate the patterns preferably employed for right and left leg and 60 the rear flap respectively. Figs. 6 and 7 show front and rear views of the garment with the leg portions pulled apart to a slight extent. Fig. 8 shows the front of the garment with the leg portions pulled far apart. 65 Fig. 9 shows the rear portion of the garment with the flap pushed to one side.

In the drawings A represents the right leg and A' of Fig. 3 the pattern for the right leg; B is the left leg and B' of Fig. 4 is the 70 pattern therefor. C, Fig. 3 and D, Fig. 4, are reinforced pieces sewed upon the patternpieces A' and B' and occupying in the finished garment the position shown in Fig. 1. The edges of the patterns A' and B' 75 marked respectively E, F and G, H are united to form the leg seams I and J. In forming the pattern shown in Fig. 3 into the leg portion of the garment the angular cut K is open to a more nearly right angle condition and is permanently incorporated in the garment by having the short edge of the cut crossed by transverse stitches L at that point of the garment where the lower end of the button carrying hem terminates. 80 The button carrying hem is the lower or under-lapping part of the garment. In the neighborhood of the stitches L the garment is permanently united by further transverse stitches L which unite the button-hole carrying hem with the button carrying hem. The edge M of the patterns A' is united longitudinally with a button hole carrying hem at the front of the garment while the edge N of the pattern A' forms the rear under-lapping section of the garment. By cutting the pattern A' as described and incorporating it in the garment in the manner stated, the point O, which in the finished garment marks the position approximately of the 85 button P, is very materially carried inward so as to be situated as far as possible to the right of the crotch in the position of the garment when worn. At this point of the right leg as the result of this construction the 90 right leg is apparently cut away so that although forming the under-lapping portion of the fabric in the crotch region the fabric composing the right leg is kept remote from the crotch itself.

Referring now to the left leg pattern shown in Fig. 4, it will be noticed that the waist line Q is a little wider than the corresponding line of the pattern A'. This is due to the fact that the facing at the top of the right leg can be eliminated in this structure and for the purpose of throwing the seat in the center of the reinforced web in the back of the garment. The rear flap R shown in Fig. 5 has its upper edge attached to the waist line. Its edge S is attached along the line of the pattern B' facing it from the waist to the seam J formed by uniting the edges G and H of the pattern B'. The further portion S of the rear flap R then crosses the seam J and it is sewed to the edge T of the pattern B'. The edge U of the rear flap R is incorporated into the permanent union formed by the seams L between the button carrying and button hole carrying hems which form the front of the garment. V is the button-hole which coöperates with the button W to close the rear flap.

In a construction formed as described it will be seen that when the garment is worn and quite irrespective of how the garment is manipulated for any purpose whatever, the over-lapping part of the rear flap R will at all times be the fabric interposed between the wearer and his outer garments in the crotch while the lower or under-lapping part is out of the way. It will be noticed that the two legs of the garment are constructed on entirely different lines. The patterns although apparently similar differ from each other in every part. Even the lines E, F and G, H are not alike, the line G being longer than the line F but shorter

than the line E or H, while the line E is longer than F and slightly shorter than the line H. These dimensions all coöperate in the production of the garment according to the principle above laid down, the curvature of the various lines E and F, G and H being also relied upon to produce the finished garment to the proper crotch construction of the character above described. The button P and its coöperating button hole may be omitted if desired. 50

What I claim is:

A union suit comprising an upper body portion having a front opening from the neck to the crotch, leg sections the upper parts of which form a continuation of the body of the garment, said leg sections being permanently united to one another solely at the lower portion of the front opening of the garment, and a rear flap permanently carried by one of said leg sections extending from the rear waist line to the aforesaid lower part of the front opening, said flap being of such size and shape as to not only completely cover the crotch but also to extend downwardly so as to cover the inside upper portion of the opposed leg of the wearer, the inside upper portion of the opposed leg section being distant from the crotch to an extent just sufficient to permit the free edge of said distant portion to be 65 covered by the free edge of the flap. 70

In testimony whereof I have hereunto set my hand in the presence of two subscribing witnesses.

EDMUND C. HEYN.
